UNITED STATES PATENT OFFICE

168,794

HELICOPTER

Dragoljub K. Jovanovich, Redondo Beach, Calif.,
assignor to McCulloch Motors Corporation, Los
Angeles, Calif., a corporation of Wisconsin

Application February 12, 1951, Serial No. 14,188

Term of patent 14 years

(Cl. D71—1)

To all whom it may concern:

Be it known that I, Dragoljub K. Jovanovich, a citizen of Yugoslavia residing at Redondo Beach, in the county of Los Angeles and State of California, have invented a new, original, and ornamental Design for Helicopter, of which the following is a specification, reference being had to the accompanying drawings, forming part thereof.

Fig. 1 is a perspective view of a helicopter showing my new design;

Figs. 2, 3 and 4 are respectively a plan view, side elevational view and front elevational view thereof, wherein several of the rotor blades are shown broken away for convenience of illustration.

I claim:

The ornamental design for a helicopter, as shown.

DRAGOLJUB K. JOVANOVICH.
